SUCTION CLEANER

Charles H. Taylor, North Canton, Ohio, assignor
to The Hoover Company, North Canton, Ohio, a
corporation of Ohio

Application February 19, 1937, Serial No. 126,653

5 Claims. (Cl. 15—16)

The present invention relates to suction cleaners in general and particularly to new and novel supporting means by which the cleaner body is adjustably supported relative to a surface covering undergoing cleaning. More specifically, the invention comprises a suction cleaner in which the cleaner body is pivotally supported upon an ambulatory chassis in such a manner that at least a part of the weight of the forward part of the cleaner is counterbalanced.

The specific nozzle height adjusting mechanism herein disclosed and described forms the subject matter of copending application Serial Number 102,883, filed September 28, 1936, now Patent 2,146,006. It is an object of the present invention to provide a new and improved suction cleaner. It is another object of the invention to provide a new and improved connection between the body and the chassis of a suction cleaner. A still further object is the provision, in a suction cleaner, of a pivoted body which is pivotally supported upon an ambulatory chassis and which is spring counterbalanced to offset at least a part of the nozzle weight. Still another object is to provide a suction cleaner in which semi-automatic adjusting means raise and lower the cleaner nozzle relative to the surface covering undergoing cleaning, and relative to its supporting chassis, there being counterbalancing means to offset at least a part of the weight of the nozzle to assist the operation of the said adjusting means. These and other more specific objects will appear upon reading the following specification and claims and upon considering in connection therewith the attached drawings to which they relate.

Referring now to the drawings in which a preferred embodiment of the present invention is disclosed, and in which the same reference character refers to the same part throughout:

Figure 1 is a side view of a suction cleaner embodying the present invention with certain parts broken away to show the semi-automatic nozzle height adjusting means and the pivotal counterbalancing connection between the cleaner body and the ambulatory chassis;

Figure 2 is a bottom view of the cleaner shown in Figure 1;

Figure 3 is an enlarged showing of the knife edge pivotal connection between the cleaner body and the chassis as illustrated in Figure 1;

Figure 4 is a transverse section, upon the line 4—4 of Figure 2, through the knife edge pivotal connection;

Figure 5 is a view in perspective of the Y-shaped chassis.

In the modern suction cleaner, the height of the suction cleaner nozzle relative to the surface covering undergoing cleaning is adjusted by means which are semi-automatic in the sense that the operator need only depress an actuating lever to effect a proper adjustment regardless of the operating conditions. By the present invention has been provided a pivotal connection 10 between a cleaner body and its supporting chassis by which the body is partially counterbalanced at its nozzle end to permit of efficient and effective nozzle adjustment by the semi-automatic means.

Referring again to the drawings, a modern suction cleaner is disclosed and comprises a body proper 1 which includes a nozzle 2 having front and rear lips 3 and 4, respectively, and which is interiorly connected by a passageway 5 to the eye 6 of a fan chamber 7. An exhaust outlet 8 leads from the fan chamber 7 and to it is removably connected a dust filter bag 9. The body 1 also includes a motor hood 10 which encloses an unshown driving motor, the shaft 11 of which 20 extends downwardly through the fan chamber 7, where it carries the suction-creating fan 12, and into the air passageway 5 where it is suitably formed as a pulley.

A rotatable agitator 13, including rigid beater 30 elements 14 and brush elements 15, is positioned within the nozzle 2 being adapted to contact the surface covering undergoing cleaning between the lips 3 and 4. A power-transmitting belt 16 connects agitator 13 to the driving shaft 11 and 35 upon the rotation of the motor agitator 13 is driven.

The entire cleaner body, together with the filter bag 9, is supported upon a Y-shaped chassis 20, perhaps best illustrated in Figure 5. The 40 chassis itself is movably supported by front wheels 18, 18 which are enclosed in the bifurcated downwardly extending forward extremities of each of the arms of the chassis and by spaced rear wheels 19, 19 positioned at the foot of the 45 Y. The chassis 20 is positioned under body 1 of the cleaner and is substantially hidden from view by the depending side walls which extend rearwardly from nozzle 2. At the base of the Y of the chassis aligned transversely extending V- 50 shaped upwardly facing channels are provided which are adapted to receive and tiltingly seat downwardly depending knife edges or shoulders 22, 22 formed on the underside of body 1 immediately thereabove.

The cleaner body is drawn to and held against the chassis 20 through the cooperation of a compression coil spring 23 which encircles a depending threaded bolt 24 carried by the underside of body 1 and which extends through a relatively large opening 25 positioned in the chassis between the V-shaped seats 21, 21. An internally threaded nut member 26 seats upon bolt 24 and contacts the lower end of coil spring 23 which is sufficiently compressed to draw the bolt and so the cleaner body downwardly. To protect spring 23 from foreign material which would otherwise collect thereon, a protector cup 27 is provided which encloses the spring and seats directly on nut 26.

It is important to note that bolt 24 is positioned rearwardly of a vertical plane through the line of contact of depending knife edge shoulders 22, 22 of the body with their seats 21, 21 on the chassis. The relationship is such that coil spring 10 pivots the rear of the body downwardly about the pivotal axis thereby tending to lift the nozzle end of the cleaner upwardly.

The nozzle adjustment means disclosed are only illustrative of the general type of adjustment with which the counterbalancing pivotal mounting which comprises the present invention is particularly effective. The particular adjustment here shown is not itself a part of the present invention, it being claimed in a co-pending application, as stated supra. The present invention, in which the cleaner body is movable relative to the supporting chassis and is counterbalanced, is important and effective in any type of adjustment in which the weight of a surface-contacting portion of the cleaner is a factor in determining the nozzle height adjustment.

The particular nozzle height adjustment illustrated includes a fixed, inclined abutment member 30 secured to the underside of body 1 and movable therewith. This abutment is contacted by a cam 31 formed upon the forward end of cam-ratchet lever 32 which is pivoted near its forward end upon a pin 33 carried by seat 34 at the forward extremity of one of the arms of Y chassis 20. A bell-crank 35 is also pivoted upon pin 33 and has at its lower and forward extremity a pin 36 which pivotally carries a pawl lever 37 formed with a dog 38 at its outer end which is adapted to seat upon the ratchet teeth at the rear end of lever 32. A coil spring 39 encircles bell-crank-carried pin 36 and contacts the crank at one of its extremities and at its other underlies pawl lever 37 urging that member upwardly at all times. In its uppermost position dog 38 of pawl lever 37 contacts an abutment 40 formed on the underside of the adjacent arm of chassis 20.

Cam-ratchet lever 32, together with bell-crank 35 and pawl lever 37, which are all carried by the chassis as distinguished from body-carried abutment 30, are adapted to form a rigid unit when the dog 38 of lever 37 is held in place by spring 39 against one of the ratchet teeth of the lever 32. This rigid unit is pivotally mounted by the pin 33 upon chassis 20 and is, in normal cleaner operation, held in a fixed position by the foot lever 45 which is pivoted by pin 46 to the chassis. Lever 45 is spring urged to an uppermost position by a chassis-carried coil spring 43 which encloses and urges upwardly the rod 44 carried by the lever 45 rearwardly of its pivot pin 46. Forwardly of the pin 46, lever 45 is formed with an arm 47 which slidably encloses a pin 48 carried by bell-crank 35.

As in the usual cleaner a handle is provided the lower bifurcated ends or arms of which extend at the side of the cleaner, as best shown in Figure 1, and which are indicated by the reference character 55. Each arm 55 extends downwardly through a slot 56 formed in the casing to be pivotally mounted upon a pin 57 carried by a seat 58 in the chassis. A coil spring 59 encircles one of the pins 57 and urges the handle forwardly, as illustrated in Figure 2, while upon the other arm 55 an arcuate sector 60 is provided which is contacted by a roller detent 61, of a common and well known type, which resistingly holds the handle in certain positions and within fixed ranges of movement.

The operation of the suction cleaner constructed in accordance with the present invention is like that of other common and well known cleaners when performing the cleaning operation. The distinction, however, from prior cleaners lies in the perfection of the nozzle height adjustment when the cleaner body is mounted to the supporting chassis, as taught by this invention. This superiority arises from the fact that in semi-automatic nozzle adjustments of the type disclosed, a pre-requisite condition to the proper adjustment of the nozzle is that the nozzle, or some part of the cleaner body as distinguished from the supporting chassis, shall rest substantially upon the very top of the covering to be cleaned in order to gauge the height thereabove to which the nozzle should be lifted. The supporting chassis cannot perform this gauging function for the weight which it supports causes it to sink into the covering. Likewise the cleaner body cannot satisfactorily perform this function if it exerts too great a force in contacting the covering. By the mounting comprising the present invention the body weight is sufficiently counter-balanced, or compensated for, that the surface contacting body part can rest on the top of the covering and will not sink therein.

Upon the cleaner embodying the present invention being placed upon a surface covering to be cleaned the first operation should be to adjust the cleaner nozzle, together with the agitator carried thereby, in proper position to operate with maximum effectiveness upon the covering. The operator accomplishes this by depressing the rear end of foot lever 45. From that point on the entire adjustment is automatic and the following takes place.

The downward movement of the foot lever 45 rearwardly of its pivot 46 causes the arm 47 thereon forwardly of that pivot to move upwardly. This movement of arm 47 is transmitted to bell-crank 35 through the pin 48, which the arm slidably encloses, and results in the counter-clockwise movement of the crank, as viewed in Figure 1. As the cam-ratchet lever 32 and pawl lever 37 are related as a rigid unit through the locking of the dog 38 of the pawl with the ratchet teeth of lever 32, the entire rigid unit pivots counter-clockwise. This, obviously, results in the downward movement of cam 31 which supports the cleaner body forward of its pivotal axis through the abutment 30.

The counter-clockwise movement of the rigid unit continues until the dog 38 of pawl lever 37 contacts abutment 40 of the chassis and, against the force exerted by coil spring 39, moves rearwardly and from the ratchet teeth. The nozzle end of the cleaner is now free to drop into contact with the supporting surface for the cam 31 no longer opposes the downward movement of

the abutment 30, although it is held thereagainst by the greater weight of the ratchet end of lever 32.

5 The exact position which the forward end of the cleaner assumes at this point is of great importance. The nozzle lips should rest upon the top of the covering without sinking therein. The downward force upon the foot lever can now be removed. The spring 43 then causes the 10 arm 47 of lever 45 to move downwardly and the bell-crank 35 to pivot clockwise, as viewed in Figure 1. As crank 35 pivots it draws pawl lever 37 along abutment 40, on which it rested, and into engagement with the ratchet teeth of cam-ratchet lever 32. The position of the cam-ratchet lever 32 at the time of this engagement, it should be noted, is determined by the position to which the lever has been pivoted by the body abutment acting on cam 31 when the body moved 15 downwardly to its surface-contacting position. Thereafter, the bell-crank 35, cam ratchet lever 32, and pawl lever 37 move as a rigid unit counter-clockwise under the force exerted by spring 43 through arm 47 until the foot lever 45 has again reached its upper and original position. This movement of the unit results, of course, in the lifting of the nozzle by the cam 31 on cam-ratchet lever 32 acting on abutment 30.

20 The height to which the nozzle is raised above the supporting surface by the adjustment may or may not be identical with its original height. Its final position is determined by what part of the cam 31 contacted the abutment at the beginning of the final lifting operation, and more 25 specifically, at the time the pawl engaged the ratchet teeth. The lower the nozzle descended the closer to its pivotal pin 33 was the point of contact of the cam 31 and abutment 30. And as the vertical lift upon the cam being pivoted varies 30 substantially directly with the distance of this contact point from the cam pivotal axis, it is clear that the function performed by the counterbalancing means in limiting the sinking of the lips into the covering is very important.

40 I claim:

1. In a suction cleaner, the combination of a 45 wheeled carriage, a body supported upon said carriage for limited tilting movement about a horizontal transverse axis offset from the center of mass of said body in a rearward direction, releasable means normally supporting said body against tilting, a bolt anchored in one and extending through an aperture in the other of said carriage and body and offset a short distance 50 from the axis of tilting movement of said body, and a spring carried by said bolt to counterbalance in part the forces acting to tilt said body when said supporting means are released.

2. In a suction cleaner, the combination of a 55 wheeled carriage, a body supported upon said carriage for limited tilting movement about a horizontal transverse axis offset from the cen-

ter of mass of said body in a rearward direction, releasable supporting means normally holding said body against forward tilting under the force of gravity, a bolt anchored in one and extending through an aperture in the other of said carriage and body and offset a short distance from the axis of tilting movement of said body, and a spring carried by said bolt and acting to counterbalance in part the action of gravity upon the 10 tilting movement of said body.

3. In a suction cleaner the combination of a carriage having wheels mounted at the front and rear ends thereof, a body mounted on said carriage for limited tilting movement about a horizontal knife-edge bearing located rearwardly of the center of mass of said body, a bolt depending from the underside of said body and through an aperture in said carriage at a point offset a short distance rearwardly of the line of said knife-edge bearing, and a compression spring carried at the 15 lower end of said bolt and bearing against the underside of said carriage, said spring acting to anchor said body upon said carriage and to counterbalance a part of the weight tending to tilt the body forwardly and downwardly.

4. In a suction cleaner, the combination of a carriage having wheels mounted at the front and rear ends thereof, a body supported upon said carriage for limited tilting movement about a transverse knife-edge bearing located rearwardly of the center of mass of said body, a bolt depending from the underside of said body and passing through an aperture in said carriage at a point offset a predetermined short distance rearwardly of the line of said knife-edge bearing, a compression spring carried at the lower 20 end of said bolt and bearing against the underside of said carriage, said spring acting to anchor said body upon said carriage and to counterbalance a part of the weight tending to tilt the body forwardly and downwardly.

5. In a suction cleaner, the combination of a carriage having wheels mounted at the front and rear ends thereof, a body supported upon said carriage for limited tilting movement about a transverse knife-edge bearing located rearwardly of the center of mass of said body, a bolt depending from the underside of said body and passing through an aperture in said carriage at a point offset a predetermined short distance rearwardly of the line of contact of said knife-edge bearing, a compression spring carried at the lower end of said bolt and bearing against the underside of said carriage, foot actuated releasable means acting normally to hold the forward end of said body against tilting in a downwardly direction, said spring acting to counterbalance a part of the weight causing said body to tilt when 40 said holding means is released.

CHARLES H. TAYLOR.
